UNITED STATES PATENT OFFICE.

WALTER C. MAJOR, OF NEW YORK, N. Y.

DESIGN FOR A PLAYING-CARD.

44,278.

Specification for Design.

Patented July 1, 1913.

Application filed April 12, 1913. Serial No. 760,829. Term of patent 14 years.

To all whom it may concern:

Be it known that I, WALTER C. MAJOR, a citizen of the United States of America and of the State of New York, and residing at No. 515 West One Hundred and Eighty-seventh street, New York city, county and State of New York, have invented a new, original, and ornamental Design for Playing-Cards, of which the following is a specification, reference being had to the accompanying drawing, forming part thereof.

The figure is a plan view of the back of a playing card, showing my new design.

I claim—

The ornamental design for a playing card, as shown.

WALTER C. MAJOR.
